MACHINE FOR GRINDING OR SHARPENING
EDGE TOOLS

Ernest G. Schulze, Jersey City, N. J.

Application December 14, 1936, Serial No. 115,839

7 Claims. (Cl. 51—80)

This invention relates generally to machines for grinding or sharpening edge-tools; and it has to do more particularly with the grinding or sharpening of cutting edges of ordinary knives.

Accordingly, in explaining the principles of the invention, reference will be made for the sake of a concrete illustrative example to this particular use, but it is to be understood that this reference is merely illustrative and not restrictive because 10 the invention is obviously applicable to the grinding or sharpening of other edge tools having one or more edges to be ground or sharpened.

The grinding or sharpening of knives, such as those used by butchers for example, has heretofore required considerable time and skill and 15 it has been difficult, even for a skilled operator, to properly sharpen a knife without producing a feather edge and without reducing the blade more than was required to produce a proper edge, 20 thus unnecessarily shortening the life of the knife. Because of these difficulties, it has been the practice for butchers and the like to have their knives sharpened by experts who make a regular business of this, but this not only involves considerable expense but is objectionable 25 for other reasons.

One of the objects of this invention is to provide a machine which will reduce to a minimum the degree of personal skill required in the grinding 30 or sharpening of knives and similar edge-tools so that persons without any particular skill can properly grind or sharpen knives and the like very conveniently and quickly.

Another object of the invention is to provide 35 a simple compact machine at low cost which will operate efficiently and automatically to accurately sharpen a knife or other edge tool in such a way as to produce a relatively long, tapering, composite edge without producing a feather edge. 40 With these and other objects in view which, together with the novel features and advantages, will become apparent from the following description taken in conjunction with the accompanying drawings illustrating one practical form of 45 machine embodying the invention, the invention comprises the novel method and machine which will first be described and explained by means of an illustrative example embodying in desirable practical form the underlying principles involved 50 and will then be more particularly pointed out in the claims.

Described generally, the invention comprises 55 contacting a side of a knife or similar edge-tool with a tapered rotating or similar moving curved peripheral abrasive surface and drawing the knife

longitudinally across and in linear contact with the periphery from the larger-diameter curved portion to the smaller-diameter curved portion to form or provide a composite cutting edge having portions extending at different angles.

The machine embodying this invention comprises opposed members, one of which comprises a rotatable or similarly movable peripheral grinding member, said members cooperating to provide a grinding path or throat substantially 10 wedge-shaped or cusp-shaped in cross-section to receive and contact an edge tool to be ground, said path varying in cross-section from one end to the other, and means for driving said grinding member. Most desirably the opposed members 15 comprise a pair of rotary tapered or conical grinding wheels mounted with their peripheries in rolling contact on a line which forms the closed bottom of the grinding path or throat and with the smaller-diameter portions thereof adjacent each other so that both sides of the knife or other edge tool will be reduced as it is passed or drawn longitudinally along said path in contact with said grinding wheels.

In order further to explain the underlying 25 principles of the invention, a specific practical embodiment of the method, and of a machine for carrying it out, will be shown in the accompanying drawings and described in detail hereinafter by way of illustrative example only and 30 not as in any way limiting the broad scope of the invention. In these drawings,

Fig. 1 is a top plan view of a machine embodying this invention, with the housing cover plate removed.

Fig. 2 is a front side elevation thereof, with the cover plate in position.

Fig. 3 is a fragmentary view looking toward the front end of the right-hand grinding wheel in Fig. 1.

Fig. 4 is a sectional view on the line 4—4 of Fig. 1, and

Figs. 5 and 6 are diagrammatic views showing the sharpening or grinding effect produced by the larger and smaller diameter peripheries, respectively, of the grinding wheels.

Referring to the drawings, the novel machine there shown may be generally described as comprising two opposed tapered or conical peripheral grinding members or wheels 10 and 11 which 50 are rotatably mounted in casing or housing 12 so that their peripheries are contiguous or in rolling contact, the grinding wheels being suitably driven in opposite directions by driving means or gearing indicated generally by 13. As 55

here illustrated, the axes of the grinding wheels are horizontally disposed, but they may be arranged at an angle to the horizontal or vertically if desired.

- 5 The specific construction and arrangement of the grinding members or wheels 10 and 11 may differ widely within the scope of the broad invention. In the particularly desirable embodiment here illustrated, each grinding wheel or 10 stone is in the form of a truncated cone having a larger diameter portion or end 10^a or 11^a and a smaller diameter portion or end 10^b or 11^b, and is formed of any suitable abrasive or grinding material, such as carborundum, for example.
- 15 The material of which the grinding wheels are made may vary in composition and hardness, as desired, and in the specific embodiment illustrated the smaller or finishing end or peripheral portion 10^b or 11^b of each grinding wheel is made 20 of a harder composition than the other parts as indicated at 10^c and 11^c in Figs. 1 and 4.

Various arrangements for mounting the rotatable grinding wheels 10 and 11 may be used. In the example illustrated they are mounted on 25 shafts or spindles 14 and 15 rotatably mounted in bearings 16 and 17 carried by U-shaped supports or yokes 18 and 19 swingably or pivotally supported on pins or shafts 20 and 21, respectively, mounted in casing 12. The shafts 14 and 30 15 are provided with square arbor portions 22 and 23 which fit into axial openings 24 and 25 provided in grinding wheels 10 and 11, respectively, the wheels being clamped in place between thrust bearing bushings 26, 26^a and washers 27, 35 27^a by screws 28, 28^a, respectively. The grinding wheels 10 and 11 are thus rotatably and swingably supported for movement toward and away from each other and in order to yieldingly hold them together with their peripheries in rolling 40 contact, contractile springs 29 and 30 are connected to casing 12 by screw 31 and to the upper swingable ends of yokes 18, 19 by screws 32, 33, respectively.

As best shown in Figs. 1 and 2, the grinding 45 wheel shafts 14, 15 and also shafts 20, 21 are arranged at an acute or oblique angle to each other. The contiguous oblique or conical peripheral surfaces or faces of the grinding wheels 10 and 11 meet on a line 34 which bisects the angle 50 formed between the shafts 14, 15 and forms the closed bottom of a cusp-shaped or wedge-shaped space 35 formed between the opposed grinding wheels, said space providing a V-shaped grinding path or throat with concave side walls to 55 receive a knife or other edge tool to be ground or sharpened. The tapered or frusto-conical grinding wheels are mounted with the larger diameter and smaller diameter portions 10^a, 10^b, respectively, of one wheel contiguous or adjacent 60 to the larger diameter and smaller diameter portions 11^a, 11^b, respectively, of the other wheel with the result that the wedge-shaped grinding path or throat 35 formed by the opposed grinding wheel peripheries gradually varies in cross-section from one end to the other. In other 65 words, the grinding throat 35^a formed by the larger-diameter portions 10^a and 11^a of the grinding wheels is narrower and forms a more acute angle (see Figs. 2 and 5) than the throat 35^b 70 (see Figs. 2 and 6) formed by the smaller-diameter portions 10^b and 11^b of said grinding wheels. From the foregoing it will be seen that when a knife blade to be sharpened is drawn longitudinally through the throat 35 and in contact with 75 and across the opposed peripheries of the grind-

ing wheels 10 and 11, the throat portion 35^a formed by the larger-diameter portions 10^a and 11^a of said grinding wheels will act to a greater extent but on a smaller angle on the sides of the knife blade than the throat portion 35^b formed by the smaller diameter portions 10^b and 11^b of said grinding wheels. This is an important feature of applicant's invention because it makes it possible to automatically grind or sharpen a knife or similar edge tool with a composite edge, which edge has a plurality of different angles formed by the different angles of the grinding path or throat.

Means are provided to equalize movement of the grinding wheels 10 and 11 toward each other 15 and to ensure that they always come together or meet at a predetermined or definite point or line centrally located relative to the casing 12. In the specific example illustrated this equalizing means (see Figs. 1, 3 and 4) comprises links 20 36, 37 pivotally connected to the lower swingable ends of yokes 18, 19, respectively and to the slide member 38 which is slidably mounted on the vertically extending rod 39 secured in sockets provided therefor in the casing 12. From 25 the foregoing it will be clear that the yokes 18, 19 and the rotatable grinding wheels 10 and 11 carried thereby are connected in such a way that swinging movement of one yoke will cause a corresponding swinging movement of the other yoke 30 so that the grinding wheels will always come together or meet at a definite desired point.

The means indicated generally at 13 for driving or rotating the grinding wheels 10 and 11 in opposite directions may be of any appropriate 35 character, but that here illustrated has certain practical advantages. As best shown in Figs. 1, 3 and 4, 40 indicates a main shaft journaled at its ends in bearings 41 and 42 provided in the interior of casing or housing 12. One end of 40 shaft 40 extends from one end of the housing and through the projecting lug 43 and is fitted with a square nut or cap 44 which is arranged to provide a connection by which shaft 40 may be driven by an electric motor or other suitable 45 driving means. The specific construction disclosed is particularly arranged to cooperate with and fit into a driving socket or connection provided by many butcher's motor-driven chopping machines in common use today, thereby eliminating the need of a separate motor and speed reducer. When using this source of power, a screw 45 mounted on the exterior of casing 12 engages the chopping machine frame-work and acts as a stop or abutment to prevent 50 relative movement or rotation of housing 12. Secured to shaft 40 are two bevel gears 46, 47 which mesh with combination bevel and spur 55 idler gears 48, 49 rotatably mounted on pins or shafts 20, 21 respectively. The spur gear portions of gear wheels 48, 49 mesh with spur gears 50, 51 secured to grinding wheel shafts 14, 15, respectively. It will be seen from the foregoing description that when main shaft 40 is driven counter-clockwise, as viewed from the right in 60 Fig. 1, grinding wheel 10 will also be driven counter-clockwise while grinding wheel 11 will be driven clockwise, as indicated by the arrows in Fig. 2. In view of the fact that gears 48, 49 are mounted on the pins or shafts 20, 21 which 65 form the axes upon which the yokes 18, 19 swing, the driving connection does not interfere with the desired swinging movement of said yokes. As a matter of fact, due to the planetary arrangement of gears 46, 48 and 47, 49, respectively, 70 75

and the fact that gears 48 and 49 are rotatably mounted on oscillatable pins or shafts 20, 21 to which the yokes 18, 19 are secured, these latter gears tend to force the upper ends of the yokes 5 and the grinding wheels carried thereby together. Thus the grinding wheels are urged together by spring pressure and by the driving means.

The housing or casing 12, which is provided with the movable cover plate 12^a, not only provides a support and housing for the mechanism, but it also provides a receptacle to receive and hold oil or other suitable lubricant for lubricating the gearing etc. A front plate or apron 52 is secured to the front side of housing 12 by screws 15 or other fastening means and provides a guard for the grinding wheels 10 and 11 as well as a pan or receptacle for holding oil or similar lubricant. The grinding wheels are adapted to dip into this oil bath so that as they rotate they 20 are covered with a film of oil which eliminates any possibility of burning the knife with the grinding wheels.

In operating the machine to carry out the method of this invention, a knife blade 53 to be 25 ground or sharpened and shown in cross-section in Figs. 5 and 6 is moved longitudinally through the grinding throat 35 in the direction of the arrow 54 in Fig. 1. The sides of the blade are first acted upon by the larger-diameter portions 30 10^a and 11^a of the grinding wheels as indicated diagrammatically in Fig. 5, the angle between the sides of the throat, formed by the opposed peripheries of the grinding wheels, and consequently the angle formed by the ground faces or 35 sides of the knife blade being comparatively small or acute. If the grinding were continued, this would result in a very thin cutting edge and produce what is known as a "feather edge", that is, an edge so thin that it bends over very easily 40 when brought into contact with bone, gristle, or other hard or tough substances. However, by continuing longitudinal movement of the knife blade through the grinding throat, the sides of the knife blade are gradually reduced on a different and wider angle until the other end of the 45 grinding path or throat is reached. This point is shown diagrammatically by Fig. 6 which shows the comparatively wide angle formed by the smaller-diameter portions 10^b, 11^b of the opposed 50 grinding wheels. From the foregoing it will be seen that by merely drawing the knife blade through the varying grinding throat from the narrow angle end to the comparatively wide angle end, the knife blade is automatically 55 profiled with a composite cutting edge with faces at many different angles and that there is no danger of producing the objectionable "feather edge" even by an unskilled operator.

It is to be understood that the invention is 60 not limited to the exact arrangements shown and described and that various modifications in construction and procedure can be made without departing from the spirit and scope of the invention as defined in the claims.

65 What is claimed is:

1. An edge-tool grinding machine comprising a rotatable grinding wheel provided with a conical periphery, a second rotatable grinding wheel provided with a conical periphery, said grinding 70 wheels being mounted for movement toward and away from each other and arranged with their peripheries in rolling contact on a line to form a grinding path which varies in cross-section from one end to the other to receive and grind 75 an edge tool passed along said path in contact

with said grinding wheels, and means pressing said grinding wheels into contact with each other.

2. An edge-tool grinding machine comprising a pair of opposed rotatably-mounted tapered 5 grinding wheels, said grinding wheels being mounted with their peripheries in rolling contact on a line to form a wedge-shaped path varying in cross-section from end to end to receive and grind an edge-tool passed along said path in 10 contact with said grinding wheels, resilient means pressing said grinding wheels into contact with each other, and means for rotating said grinding wheels.

3. An edge-tool grinding machine comprising 15 a pair of opposed rotatably-mounted tapered grinding wheels, said grinding wheels being mounted with their peripheries in rolling contact on a line to form a wedge-shaped path varying in cross-section from end to end to receive and 20 grind an edge-tool passed along said path in contact with said grinding wheels, means urging said grinding wheels toward each other, and means equalizing the movement of said grinding 25 wheels toward each other.

4. A knife sharpening device comprising two pivoted supports movable toward each other, rotatable members each provided with a tapered peripheral abrasive surface and mounted one on each support adjacent a swinging end thereof, 30 said rotatable members being arranged with their peripheries in rolling contact on a line to form a V-shaped path varying in cross-section from end to end to receive and abrade a knife blade 35 passed along said path in contact with said members, and resilient means pressing said supports toward each other and said rotatable members together.

5. A knife sharpening device comprising two 40 rotatable shafts disposed at an acute angle relative to each other, two rotatable members each provided with a peripheral abrasive surface arranged at an oblique angle relative to its axis of rotation, said members being mounted, one on each shaft, with their oblique peripheral surfaces 45 in contact to form therebetween a continuous V-shaped throat which varies in cross-section from end to end to receive and abrade a knife blade passed through said throat in contact with said members, and means for urging one shaft 50 toward the other to maintain the rotatable members in contact.

6. An edge-tool grinding machine comprising two supports movable toward each other, pivots for said supports, tapered grinding wheels rotatably mounted one on each support adjacent a swinging end thereof and with their peripheries in rolling contact on a line to form a wedge-shaped path varying in cross-section from end to end to receive and grind an edge-tool passed 55 along said path in contact with said grinding wheels, gear wheels rotatably mounted one on each support and operatively connected to the grinding wheel mounted on said support to swing therewith, idler gear wheels rotatably mounted 60 one on each pivot, and drive gear wheels for rotating said idler gear wheels in opposite directions, said idler gear wheels each meshing with a gear wheel carried by a support and so disposed relative thereto that they drive the said gear 65 wheels carried by the supports and simultaneously urge the supports and the grinding wheels carried thereby toward each other.

7. An edge-tool grinding machine comprising a 75 housing, two supports movable toward each

other, pivots for said supports mounted in said housing, tapered grinding wheels rotatably mounted one on each support adjacent a swinging end thereof and with their peripheries in rolling contact on a line to form a wedge-shaped path varying in cross-section from end to end to receive and grind an edge-tool passed along said path in contact with said grinding wheels, gear wheels rotatably mounted one on each support and operatively connected to the grinding wheel mounted on said support to swing therewith, idler gear wheels rotatably mounted one on each pivot,

drive gear wheels for rotating said idler gear wheels in opposite directions, a drive shaft rotatably mounted in said housing and carrying said drive gear wheels, and means for rotating said drive shaft, said idler gear wheels each meshing with a gear wheel carried by a support and so disposed relative thereto that they rotate the said gear wheels carried by the supports and simultaneously urge the supports and the grinding wheels carried thereby toward each other.
